UNITED STATES PATENT OFFICE.

TURNEY E. BUCK, OF CHICAGO, ILLINOIS.

SCREW-SPIKE.

1,186,168.

Specification of Letters Patent.

Patented June 6, 1916.

Application filed April 24, 1913. Serial No. 763,364.

To all whom it may concern:

Be it known that I, TURNEY E. BUCK, a citizen of the United States, residing at Chicago, in the county of Cook and State 5 of Illinois, have invented a new and useful Screw-Spike, of which the following is a specification.

This invention relates primarily to means for securing the rails of railroad tracks to 10 the ties or other supporting structure.

The primary purpose of the invention is to provide a rail-fastening device adapted to fixedly attach a rail supporting device to the tie, and in the same unit a structural 15 adaptation to detachably connect the rail with its support, while permitting at the same time the removal and adjustment of the rail without disturbing the spike or the plate attached therewith. I further provide 20 in the said device means whereby to lock the nut and rail in any position. And I further propose in said invention to provide means for preventing an over-turning or spreading of the rail.

25 I illustrate my invention in the accompanying drawings in which:

Figure 1 shows a plan view of my invention. Fig. 2 shows a modified form of the same, and Fig. 3 is a diagrammatic view of 30 a structure embodying my invention, the tie, the tie-plate or chair, the rail clips, the nut and the keys being shown in section. In this view a screw spike provided with a nut is shown on one side of the rail and a screw spike without a nut is shown on the other 35 side of the rail.

In Fig. 1, a spike is shown whose lower section 1 is screw-threaded and of ordinary screw structure. I provide at 2 a tapered 40 shoulder adapted to co-act with a countersunk hole in the tie plate. At 3 I provide a circular shank to receive the lateral strain of the rail, and at 4 I provide a threaded section adapted to receive a nut. At 5 I 45 provide a polygonal end to said spike adapted to co-act with a wrench or other similar tool used for driving a screw into a tie.

In Fig. 2, I show a modified form of my 50 invention in providing a square shoulder at 2 adapted to rest upon a tie plate and bring the same into solid contact with the tie; and a circular elongated head 3. I also provide a longitudinal slot transversely perforating 55 the spike at the point 7 in the head of the spike.

At 6 I show a key of ordinary type adapted to be inserted in the slot 7. If the nut 8 be used the key will bear on the upper face of the nut. If the nut be dispensed 60 with, the key will bear on the upper face of the clip 9, the intention being to effect a device, which in general use has three locking means as a multiplied security in attaching rails to ties. It is well known that with 65 the ordinary type of spike the instant it begins to move there is no security to the rail; either vertically or horizontally; and with the ordinary screw-spike its action is single in that to remove the rail the entire spike 70 needs to be removed, and any injury to the upper part of the spike begins to release the whole attaching supporting mechanism. It will be observed in the structure which I 75 claim as my invention, that the tie plate or chair (supporting rail) can be firmly attached and retained in its fixed position by means of my device, independently of the rail and its attaching device: and it will be further observed that the removal of the 80 rail, or an injury to it or its attaching device, does not of necessity affect the integrity of the tie plate or the body of the spike in its relation to the tie. It will be further observed that my device provides 85 the strongest part of its structure at a point of the greatest strain, and thus is best able to resist lateral thrusts of the rail. Further, it will be readily observed that this structure provides the least proportion of loss 90 occasioned by wear and tear and change in rail-setting, in that once the spike is set, the only parts necessary to be removed—or which are liable to change—are the nut and clip. 95

The form as here shown is intended to cover such reasonable variations as are apparent to the ordinary mechanical mind.

I claim:

1. The combination in a device of the 100 character described, of a lower body portion having the elements of an ordinary screw; an elongated head of larger diameter than the lower screw—its lower portion forming a shoulder; said head being provided with 105 a shank, surmounted by a threaded body portion adapted to receive a nut; an upper portion of said body of smaller diameter and polygonal in shape; an elongated slot transversely perforating said head. 110

2. In a device of the character described the combination in a spike of a screw-

- threaded portion adapted to penetrate the tie, an enlarged elongated circular head having a threaded portion thereon adapted to receive a nut, and a body portion to sustain 5 a thrust; an elongated slot transversely piercing said threaded elongated head: said head terminating in a polygonal part adapted to receive a tool for turning said lower screw-threaded portion: a key adapted to 10 seat in said slot and lock the nut.
3. In a device of the character described, a spike having its lower portion conforming to an ordinary screw; having a shoulder adjacent to the shank of the screw-threaded 15 portion; and ending in an enlarged elongated head; adjacent to said shoulder a blank portion adapted to bear the lateral thrust of the rail; and the body of said elongated head being perforated with a longitudinal transverse slot: adjacent to and forming 20 a terminus of said head a polygonal portion; a key adapted to be seated in said slot.
4. The combination, in a spike, of a threaded portion adapted to thread into the tie; means on said spike adapted to clamp the chair or tie plate to the tie, and retain it, fixedly and independently of means for gripping or clamping the rail: means on 25 said spike for detachably fixing, adjusting or removing the rail, independently of the tie attaching means; means for turning or screwing said spike into the tie: means for locking the rail clamping means.
5. In a device of the character described, the combination of means for threading into a tie and firmly gripping the tie plate or chair supporting the rail; and in the same 30 unit independent means for detachably securing and gripping the rail, and locking the attaching means.
6. In a device of the character described, the combination of means for threading into the tie; a shoulder on said device adapted to bring tie and tie-plate into rigid contact; means on said device independent of said tie attaching means, for detachably fixing the rail to the tie, without disturbing the connecting device connecting the rail with the ties or other support; means for locking the 35 tie-affixing means: means for advancing the screw to its seating in the tie.
7. In a screw-spike, the combination of a screw-thread for attaching to a tie or rail supporting device; a threaded portion 40 adapted to receive a nut; a nut thereon, beveled on its lower side, said nut adapted to co-act with and press upon a rail; a polygonal portion adapted to supply means for advancing said spike into a tie; means for locking said nut when driven to its seating.
8. In a screw-spike, the combination of a threaded portion for screwing into a tie; an enlarged elongated head portion; a shoulder at the junction of the screw and the head 45 portions; on the enlarged head portion—adjacent to said shoulder—a circular shank adapted to co-act with a hole in a clip or receive the lateral thrust of a rail; a threaded portion adjacent to said shank—adapted to receive a locking nut; an elongated longitudinal slot transversely perforating the said threaded head portion, adapted and intended to receive a locking key; a polygonal terminal head of diameter smaller than said 50 threaded head, and adjacent thereto.
- Signed by me at Chicago, Illinois, this 14th day of April, 1913.
- TURNEY E. BUCK.
